UNITED STATES PATENT OFFICE.

EUGENE BABER ADAMS, OF IRENTON, OHIO.

VENDING-MACHINE.

1,373,582.

Specification of Letters Patent.

Patented Apr. 5, 1921.

Application filed October 10, 1918. Serial No. 257,625.

To all whom it may concern:

Be it known that I, EUGENE BABER ADAMS, a citizen of the United States, residing at Ironton, in the county of Lawrence 5 and State of Ohio, have invented certain new and useful Improvements in Vending-Machines, of which the following is a specification.

This invention relates to an improved 10 machine for vending stamps, tickets, coupons, or the like, but is more particularly designed for use as a stamp vending machine and has as its primary object to provide a device of this character wherein a 15 given number of stamps will be delivered when a proper coin is deposited in the machine and its dispensing mechanism released.

The invention has as a further object to 20 provide a machine adapted to dispense a strip of stamps from a suitable stamp roll and wherein, when the dispensing mechanism is released, a certain predetermined length of the strip and accordingly a pre- 25 determined number of stamps, will be delivered from the machine when the stamps so delivered may be torn off from the remainder of the strip.

A still further object of the invention is 30 to provide a vending machine having a check controlled actuating mechanism for the dispensing mechanism and of such character that coins of the proper denomination only may be deposited in the machine.

The invention has as a further object to pro- 35 vide a construction wherein when the check controlled actuating mechanism is released after the deposit of a coin, the coin will be automatically freed from the said mechanism 40 to the end that only the proper number of stamps will be delivered by the dispensing mechanism for each coin deposited.

And the invention has as a still further 45 object to provide a vending machine which will be characterized by simplicity of construction, which will not be liable to get out of order, and which will be entirely dependable in its operation.

Other and incidental objects will appear 50 during the course of the detailed description of the invention. In the drawings, wherein I have illustrated the preferred embodiment of the invention, and wherein similar

reference characters designate corresponding parts throughout the several views:

55

Figure 1 is a perspective view of my improved vending machine,

60

Fig. 2 is a detail perspective view showing one side wall and the door of the casing of the device detached,

65

Fig. 3 is a side elevation, one side wall of the casing being removed,

70

Fig. 4 is a top plan view, the casing being shown in section,

75

Fig. 5 is a side elevation, the opposite side wall of the casing being removed.

125

In carrying the invention into effect I employ an oblong base 10 upon the upper face of which is screwed or otherwise secured a bed plate 11 resting flat against the base. Fitting around said bed plate and resting upon the base is an upstanding casting having a front wall 12, a top wall 13 and a rear wall 14. These walls are preferably formed from a single piece of suitable sheet metal and, as particularly shown in

130

Fig. 1 of the drawings, the front wall 12 curves gradually into the top wall 13 while the back wall 14 is disposed at substantially right angles to the flat portion of the top wall and parallel to the flat portion of the front wall. Secured upon the bed plate 11,

135

at the corners thereof, are angle plates 15 and connecting the front and back walls at their lower corners with these angle plates are screws or other suitable fastening devices 16. Closing one side of the casing is a side wall 17 provided at its front, rear and top edges with a flange 18 fitting snugly within the top, front and back walls of the casing and cut away at its lower ends, as shown in Fig. 3, to receive the adjacent angle plates 15. Secured to the inner face of said flange is a plurality of lugs 19 and loosely fitted through the walls 12, 13 and 14 of the casing and threaded into these lugs, are screws or other suitable fastening devices 20 detachably securing the side wall in position. Mounted within the upper portion of the casing at its opposite side, is a side wall 21 with which coacts a door 22 closing the adjacent side of the casing. The side wall 21 is provided at its front, rear and top edges with a flange 23 snugly fitting within the front, back and top walls of the casing and secured to the inner face of said flange is a plurality of lugs 24 into which are threaded screws or other suitable fastening devices 25 extending freely through the walls 12, 13 and 14 for detachably securing said side wall in position. At its lower edge this side wall is provided upon its inner face with a reinforcing strip 26 and mounted upon said strip substantially midway of its ends is a block 27. The door 22 is formed at its end edges with flanges 28 snugly fitting between the front and back walls of the casing and, at its lower edge, is equipped upon the inner side thereof with spaced brackets 29 which are presented downwardly and normally engage within suitable openings 30 in the bed plate 11. Supporting the door at its upper extremity are stop lugs 31 secured to the inner faces of the front and back walls of the casing and engaged by the door at its upper corners. At its upper edge a suitable lock 32 is secured to the inner face of the door and the bolt 33 of this lock is, as particularly shown in Fig. 6, projectable to engage behind the block 27 upon the side wall 21. The lock will thus serve to removably secure the door in position, the door in effect providing one section of the adjacent side wall of the casing, the other section of which side wall is formed by the fixed portion thereof.

Mounted upon the bed plate and housed within the casing are spaced vertical supporting members or frame plates 34 and 35. These plates are secured to the bed plate 11 by a plurality of angle brackets 36 and are connected and supported in parallel relation by a plurality of tie bolts 37. As particularly shown in Figs. 3 and 5 of the drawings, the forward and upper edges of the plates are curved to snugly fit the ad-

jacent curved surface of the casing. The check controlled actuating mechanism of the present invention is mounted upon these supporting plates as well as the dispensing mechanism. I shall first describe the actuating mechanism in detail and will then proceed to a detail description of the dispensing mechanism.

Journaled through the supporting plates 34 and 35 adjacent the lower rear corners thereof is a transversely arranged main drive shaft 39 to which is connected at one end a power spring 40 located between the plates. The opposite end of this spring is secured to the adjacent one of the tie bolts 37 (see 38, Fig. 6) located at the lower rear corners of the supporting plates so that this spring will thus tend to rotate the shaft in a counter-clockwise direction. At one end, the shaft is extended beyond the plate 34 toward the door 22 and is formed with a squared terminal 41, for receiving a winding key. Fixed to the opposite end of said shaft at the outer side of the plate 35 is a drive gear 42. Journaled through the plates above the shaft 39 is a countershaft 43 and fixed to one end of this shaft to mesh with the gear 42 is a pinion 44. Secured upon the shaft 43 at the inner side of this pinion and confronting the plate 35 is a gear wheel 45 and journaled through the plates above this wheel is a shaft 46 to one end of which is secured a pinion 47 meshing with the gear wheel 45. Fixed upon the shaft 46 at the inner side of the plate 35 is a gear wheel 48 and journaled through the plates above this gear wheel is a governor shaft 49. The governor shaft carries a pinion 50 meshing with the gear wheel 48, and a suitable governor 51 located between the supporting plates. As will be clear, rotary movement of the shaft 39 will be communicated to the governor shaft 49 to be controlled by the governor 51. Fixed to the shaft 43 at the outer side of the plate 34 is an escapement wheel 52 provided with a series of spaced radial teeth or lugs 53. As particularly shown in Fig. 7 of the drawings, the outer edges of these lugs are formed with cam faces 54 and the rear edge of each lug is cut away to form the straight radial face or shoulder 55 of the next successive lug. Threaded into the plate 34 at the rear of the escapement wheel and in a plane somewhat above the axis of said wheel, is a stub shaft 56 upon which is journaled at a point intermediate of its ends, a pivoted latch or detent 57 spaced from the plate by a boss 58 upon the latch. At its forward end the latch projects over the escapement wheel 52 and is provided with a laterally and downwardly directed latch pawl 59 adapted to coöperate with the lugs 53 of said wheel. At its rear end, the latch is provided with an upwardly directed terminal 60 into which is threaded

a laterally projecting pin 61 extending inwardly with respect to the latch and having journaled thereon a roller 62. Fitted over the boss 58 of the latch is a helical spring 63, 5 one end of which is inserted through a suitable opening in the plate 34. The opposite end of this spring is extended to engage beneath the roller 62 so that the spring will thus act to constantly hold the latch pawl 59 10 in engagement with the escapement wheel 52 to coöperate therewith.

Fixed to the outer side of the plate 34 above the escapement wheel 52 and latch 57, is a rearwardly and downwardly inclined 15 coin chute 64 supported by spaced brackets 65 embracing the chute and secured at their upper ends by screws or other suitable fastening devices to the plate. At its outer end the chute is arranged to register with a coin 20 slot 66 in the casing and formed on the side edges of the chute for receiving a coin inserted through this slot are inwardly directed flanges 67 which extend throughout the major portion of the length of the chute. 25 These flanges are spaced from the body wall of the chute and are arranged such distance apart that coins of the proper denomination only may be inserted in the chute. At its inner end, the chute is formed with a longitudinally 30 extending offset portion 68 projecting over the roller 62 of the latch and formed in its lower edge with a notch 69 normally receiving said roller. Formed on the inner end of the offset portion at its lower edge is 35 a substantially arcuate lateral flange 70 forming a coin pocket 71 at the junction of said offset portion with the main body of the chute. This pocket opens, as particularly shown in Figs. 3, 8 and 9 of the drawings, toward the notch 69 and is normally obstructed at its outer side by the roller 62 of the latch. At its inner end the upper flange 67 of the chute is provided with a 40 downwardly curved portion 72 for directing 45 a coin into the pocket 71 and formed on the upper edge of the offset portion 68 of the chute is an overhanging stop flange 73. This stop flange is arranged at an angle to the length of the offset portion, being inclined 50 downwardly from its inner end toward its outer end to provide an outwardly tapering throat 73' between the flange and the roller 62. The major width of this throat between the inner end portion of the flange 73 and 55 the outer end of the flange 70 is such that a coin of the proper denomination only can pass therethrough. Mounted at the outer side of the plate 34 below the coin chute 64 is a downwardly and rearwardly inclined 60 plunger 74. Adjacent its outer extremity the plunger is slidably supported by spaced guides 75 and 76, which embrace the plunger and are secured at their ends to the plate by screws or other suitable fastening devices. 65 Adjacent its inner end the plunger is slidably supported by a guide bracket 77 suitably secured to the outer face of the plate and is held against possible upward canting at its inner end by a guide pin 78 projecting laterally from the plate to overhang the 70 plunger between the guide 76 and bracket 77. At its outer end the plunger projects freely through a suitable opening in the front wall of the casing at a point just below the coin slot 66 and is equipped with a head or button 75 79. At its inner end, the plunger is, as particularly shown in Fig. 8, provided with a curved edge to fit the periphery of a coin and is adapted to be slidably received through a suitable opening 80 formed 80 through the upper end of the flange 70 of the coin pocket 71. Threaded into the plunger between the guides 75 and 76 is a screw 81 and connected at one end to this screw is a helical spring 82, the opposite end of which is connected to a screw 83 threaded into the guide 75. As will be clear, the plunger may be readily depressed against the action of this spring to project the inner end of the plunger through the opening 80 85 90 in the flange 70 of the coin pocket 71, the screw 81 being adapted to abut the guide 76 for limiting the plunger in its inward movement. Upon the release of the plunger the spring will immediately act to retract the 95 plunger to its normal position having the inner end thereof withdrawn through said opening of the coin pocket flange and disposed at the periphery of the pocket. Threaded into the plunger below the guide 100 76 is a stop screw 84 adapted to engage said guide for limiting the plunger in its outward movement.

As will now be understood in view of the preceding description, a coin inserted 105 through the slot 66 say, for instance, a dime, will travel down the chute 64 to engage the curved portion 72 of the upper flange of the chute when the said coin will be directed by the curved portion of said flange to drop into the coin pocket 71. The coin will then encounter the roller 62 of the latch 57 as well as the flange 73 at the inner end of the throat 73' to be arrested in its movement and confined within the coin pocket supported by the flange 70. Depression of the plunger 74, 110 will then project the inner end of the plunger into the coin pocket and force the coin into the reduced throat 73' when the coin will bear between the flange 73 and the roller 62 of the latch for depressing the outer end of the latch and swinging the inner end of the latch upwardly so that the latch pawl 59 will clear the shoulder 55 of the adjacent lug 53 of the escapement wheel 52. At this 115 time, the latch pawl will, as shown in detail in Fig. 8, rest against the forward end of the cam face 54 of said lug while the coin will be disposed beyond the vertical center of the roller 62, lying within the reduced 120 125 130

throat 73' between the flange 73 and the roller. However, as soon as the latch pawl is moved out of engagement with the shoulder of the lug, the tension of the spring 40 5 on the shaft 43, tending to rotate this shaft, will immediately turn the escapement wheel 52 when the latch pawl 59 will ride over the cam face 54 of the lug so that the inner end of the latch will be lifted by said cam face 10 and the outer end of the latch accordingly swung downwardly to free the coin from within the reduced throat 73' and cause the said coin to fall within the rear portion of the casing. This construction provides an 15 arrangement whereby should the plunger 74 be moved slowly inward in an attempt to permanently wedge the coin within the reduced throat 73' between the flange 73 and the roller 62 of the latch, so that the latch 20 would be permanently held out of engagement with the escapement wheel, the escapement wheel will, nevertheless, when released, act upon the latch to automatically free the coin and release the latch. When so released, 25 the spring 63 will, as previously described, hold the latch pawl bearing against the cam face 54 of the escapement wheel lug to ride around the escapement wheel and engage the shoulder 55 of the next successive lug of said 30 wheel when the escapement wheel will be arrested in its turning movement by the latch. This operation will, of course, be repeated each time a coin is deposited in the machine and the plunger operated to release the latch, 35 the latch being adapted to coöperate, in the manner just described, with each successive lug of the escapement wheel so that the said wheel will be permitted to turn a predetermined distance only each time it is released. 40 This feature is of importance since, as shall presently appear, the number of stamps delivered by the dispensing mechanism for each coin deposited is governed by the stepped movement of the escapement wheel. 45 The dispensing mechanism of the present invention will now be taken up. Journaled through the plates 34 and 35 in advance of the driven shaft 43 is a transverse shaft 85 to one end of which is fixed, at the outer 50 side of the plate 35, a gear wheel 86 meshing with the gear wheel 45 upon the driven shaft. Fixed to the shaft 85 at the inner side of the plate 35 is a gear wheel 87 and journaled through the plates in advance of 55 said shaft is a transverse feed roller shaft 88. Formed in the periphery of this shaft at the inner side of the plate 35 are gear teeth 89 meshing with the gear wheel 87 upon the shaft 85 so that, as will be clear, rotary 60 movement of the driven shaft 43 will be imparted to the feed roller shaft 88. Fixed to the adjacent extremity of the shaft 88 at the outer side of the plate 34 is a feed roller 90 to the inner end of which is screwed or otherwise secured a gear wheel 91 and interposed

between this gear wheel and said plate is a washer 92 surrounding the shaft. Mounted upon the outer side of the plate immediately in advance of the escapement wheel 52 is a laterally projecting bracket 93 provided at 70 one end, as particularly shown in Fig. 10 of the drawings, with a laterally directed terminal 94 which may be secured by screws or other suitable fastening devices to the plate. The opposite end of the bracket is formed 75 with an upstanding arm 95 and journaled between this arm and the plate 34 is a transverse yoke shaft 96. Mounted at their inner ends upon the opposite end portions of this shaft are spaced parallel yoke arms 97 and 80 mounted upon the outer ends of said arms is a transverse feed roller shaft 98. As particularly shown in Fig. 11 of the drawings, the shaft 98 is freely fitted through the outermost arm and removably threaded at 85 its inner end through the innermost arm. Journaled upon this shaft between the yoke arms is a feed roller 99 bearing over the feed roller 90. At its outer end the roller 99 is provided with a radial guide flange 100 overlapping the outer end of the roller 90 and screwed or otherwise secured upon the inner end of the former feed roller is a gear wheel 101 meshing with the gear wheel 91 upon the latter feed roller. The feed roller 99 is thus 90 adapted to provide an idler roller which will be driven from the feed roller 90. Wound at its end portions around the shaft 96 is a spring 102 the ends of which are engaged over the yoke arm 97 while the intermediate 100 portion of said spring is extended from the shaft and engaged against the rear edge of the bracket 93. This spring will thus act to yieldably hold the roller 99 in frictional engagement with the roller 90 while, when desired, the roller 99 may be readily swung upwardly to permit a stamp strip to be threaded between the rollers. Formed in the periphery of the roller 90 is, as shown in detail in Fig. 12 of the drawings, a transverse slot 110 103 at one side of which the roller is formed with a communicating deeper slot 104, both of these slots extending the full width of the roller. Snugly fitted in the slot 104 is a removable gripping and indenting bar 105 115 provided at its upper edge with spaced gripping teeth 106. Formed in the periphery of the roller 99 to receive the teeth 106 of the bar 105 is a transverse slot 107 and at one side of this slot this roller is provided with 120 a communicating deeper slot 108. The slots 107 and 108 extend the full width of the roller and snugly fitted in the slot 108 is a removable indenting and gripping bar 109 125 provided at its outer edge with spaced gripping teeth 110 projecting from the periphery of the roller and adapted to be received within the slot 103 of the roller 90. The teeth of the bar 105 are preferably staggered with respect to the teeth of the bar 109 130

and, at its outer end, the bar 109 is, as particularly shown in Fig. 11, provided with a lateral head 111 lying flush with the flange 100 of the roller 99. At their inner ends 5 these bars abut the gear wheels 91 and 101 of the rollers.

Connected at one end to the bracket 93 is an arm 112 which projects beneath the bracket toward the plate 34 and carries, at 10 its opposite end, an upwardly inclined stamp strip guide 113 terminating at its outer end, as particularly shown in Fig. 10, between the rollers 90 and 99 at the rear thereof. Extending from between the rollers 15 at their forward sides is a delivery guide 114 suitably connected to the front wall 12 of the casing and communicating with a delivery opening 115 therein. At their inner ends, the top and bottom walls of this guide 20 are each provided with a series of transversely spaced guide fingers 116, one series of fingers being disposed to closely confront the peripheral face of the roller 90 while the other series of fingers is disposed to closely 25 confront the peripheral face of the roller 99 for receiving the free end of a stamp strip projected between the rollers and directing said strip through the delivery guide. Mounted at the outer side of the plate 34 30 below the guide 113 is a stamp roll spool including a spool sleeve 117 at one end of which is formed an integral head 118. At its outer end the sleeve is provided with a reduced extension 119 and snugly fitted over 35 this extension is a removable head 120. Fitted through the sleeve is a screw bolt 121 threaded at its inner end through the plate 34 for connecting the spool with the plate and interposed between the inner head 118 40 of the spool and the plate is a washer 122. By removing the head 120, a stamp roll, as conventionally illustrated at 123, may be readily positioned upon the spool when the stamp strip 124 may be led from the roll and 45 through the guide 113 to be engaged at its free end between the feed rollers 90 and 99. The device is then ready for use.

As will now be understood, when a coin is deposited in the coin chute 64 and the 50 plunger 74 is actuated to release the escapement wheel 52, as previously described, the feed roller 90 will be driven, and this roller will in turn drive the feed roller 99 for feeding the stamp strip 124 between the rollers, 55 and through the delivery guide 114 to be projected out through the delivery opening 115 of the casing. The gear ratio between the shaft 43 of the escapement wheel and shaft 88 of the feed roller 90 is such that 60 when the escapement wheel is thus released, the roller 90 will be turned a complete revolution and, of course, the roller 99 will, therefore, also be turned a complete revolution. Therefore, the respective circumfer- 65 ence of these rollers will determine the

length of the stamp strip projected at each actuation of the dispensing mechanism and, in the present instance wherein the check control mechanism is designed to be actuated upon the deposit of a dime in the machine, the circumference of each of the rollers 90 and 99 is such that four two cent stamps at the free end of the strip will be advanced between the rollers. Consequently, for each dime deposited, four two 70 cent stamps will be delivered by the machine. The stamps thus delivered or the free outer end of the strip may then be grasped and the strip torn off at the gripping members 105 and 109 for freeing the 75 stamps purchased. In this connection, it will be noted that since each of the rollers 90 and 99 revolve only once each time the dispensing mechanism is actuated, the gripping members 105 and 109 will be brought 80 into contact with the stamp strip at an interval of each four stamps of the strip, when the teeth 103 and 106 of said gripping member will bear into the strip between each fourth stamp and the next adjacent stamp for firmly gripping the strip between the feed rollers. Consequently, the stamps projected between the rollers from the machine may be easily torn off at the gripping members, while at the same time, 90 possibility of drawing the stamp strip between the rollers and thus unwinding the whole stamp roll, will be effectually overcome. If desired, the teeth of the gripping members may be sharp so that the said teeth 100 will act to perforate the stamp strip but, in any instance where the strip has been previously perforated, the teeth of said members may, if preferred, be only sharp enough to indent the stamp strip, and effectually grip 105 the strip between the feed rollers.

Having thus described the invention, what is claimed as new is:

1. A vending machine including dispensing mechanism, and actuating mechanism for said dispensing mechanism, said actuating mechanism including a driven escapement wheel, a coin chute above the escapement wheel and deflected beyond the same to form a coin pocket and having an open-bottom restricted throat beyond said pocket, a latch having one end normally restraining the escapement wheel and its other end normally blocking the throat, and means adapted to force a coin from the coin pocket 110 across the end of the latch in the throat whereby the latch will be released from the escapement wheel and the coin discharged 115 through the bottom of the throat.

2. A vending machine including dispensing mechanism, and means for actuating said dispensing mechanism, said actuating means including a driven escapement wheel, a coin chute provided at its inner end with an offset portion forming a coin pocket, the 120

bottom of the coin chute being cut-away beyond the pocket, an overhanging stop flange on the upper edge of the coin chute beyond the pocket extending into the path 5 of a coin issuing from the pocket, a latch having one end normally restraining the escapement wheel and its opposite end blocking egress from the coin pocket, and means for projecting a coin from the pocket 10 against the stop flange and across the latch whereby to release the latch from the escapement wheel and discharge the coin.

3. A vending machine comprising a casing, a downwardly and inwardly inclined 15 coin chute mounted in the casing and provided near its inner extremity with a downwardly projecting offset portion constituting a coin pocket, the coin chute being reduced beyond the coin pocket and provided 20 with an overhanging downwardly inclined flange whereby an open-bottom restricted throat is provided, a driven escapement wheel mounted below the chute and between

the front wall of the casing and the inner end of the chute, a latch pivoted between 25 its ends at a point between the escapement wheel and the chute, the forward end of the latch being constructed to engage and restrain the escapement wheel and the rear end of the latch being constructed to lie 30 normally across the coin pocket at the junction of the same with the throat, yieldable means acting on the latch to hold it in normal position, and a plunger slidably mounted in the casing below the coin chute and 35 having its inner end projecting through the front wall of the coin pocket to engage a coin therein and project the coin across the end of the latch and against the overhanging flange whereby the latch will be released from the escapement wheel and the coin discharged through the open bottom 40 of the throat.

In testimony whereof I affix my signature.

EUGENE BABER ADAMS. [L.S.]
